STERILIZER FOR OPEN END CONTAINERS

Frank Haloski, Downers Grove, Ill., and Rudolph A. Adams, Eau Claire, Mich., assignors to Vacuum Can Company, Chicago, Ill.

Filed Nov. 1, 1960, Ser. No. 62,702

Term of patent 14 years

(Cl. D9—2)

FIGURE 1 is a top perspective view from the front and one side of a sterilizer for open end containers showing our new design;

FIGURE 2 is a top plan view thereof on an enlarged scale and rotated 45° to the left, and;

FIGURE 3 is a front elevational view thereof on an enlarged scale, the brush and bracket being broken off for convenience of illustration.

We claim:

The ornamental design for a sterilizer for open end containers.
